CLAIM

The ornamental design of an interchangeable entrance staircase for mobile homes and the like, as shown and described.

DESCRIPTION

FIG. 1 is a perspective view of a novel interchangeable entrance staircase for mobile homes and the like incorporating my new design;

FIG. 2 is a front elevation thereof;

FIG. 3 is a right side elevation thereof;

FIG. 4 is a plan view thereof; and

FIG. 5 is a rear elevation thereof.
